WHEEL TRIM

Howard M. Jenkins, Jr., Detroit, Mich., assignor to Van Auken, Inc., Detroit, Mich., a corporation of Michigan

Application January 29, 1953, Serial No. 23,340

Term of patent 14 years

(Cl. D14—30)

To all whom it may concern:

Be it known that I, Howard M. Jenkins, Jr., a citizen of the United States, residing in Detroit, Wayne County Michigan, have invented a new, original, and ornamental Design for a Wheel Trim, of which the following is a specification, reference being had to the accompanying drawings, forming a part thereof, in which

Fig. 1 is a front elevational view of a wheel trim embodying my new design; and

Fig. 2 is a side elevational view thereof.

The characteristic features of my design reside in the spokes having the configuration and arrangement as shown.

The phantom disclosure of a wheel in Fig. 2 is shown only for the purpose of illustration.

I claim:

The ornamental design for a wheel trim, as shown and described.
